UNITED STATES PATENT OFFICE.

GEORGE W. MACKENZIE, OF BEAVER, PENNSYLVANIA, ASSIGNOR, BY DIRECT AND MESNE ASSIGNMENTS, OF TWO-THIRDS TO WILLIAM J. ARCHER, OF VANPORT, PENNSYLVANIA.

COIN-CONTROLLED VENDING-MACHINE.

SPECIFICATION forming part of Letters Patent No. 759,535, dated May 10, 1904.

Application filed October 2, 1902. Serial No. 125,646. (No model.)

To all whom it may concern:

Be it known that I, GEORGE W. MACKENZIE, a citizen of the United States, residing at Beaver, in the county of Beaver and State of Pennsylvania, have invented certain new and useful Improvements in Coin - Controlled Vending Apparatus, of which the following is a specification, reference being had therein to the accompanying drawings, forming part 10 of this specification, in which—

Figure 1 is a face view in elevation, partly broken away, of my improved coin-controlled vending-machine. Fig. 2 is a side view thereof. Fig. 3 is a horizontal sectional view on the line III III of Fig. 1. Fig. 4 is a perspective detail view, on an enlarged scale, showing the push-bar and its connected mechanism and the coin-controlled locking-arm, the parts being in their normal position. Fig. 5 is a partial vertical sectional view indicated by the line V V of Fig. 3, the rotating carrying-wheel having been removed. Fig. 6 is a partial sectional view illustrating the action of the coin to unlock the locking-arm, so as to release 25 the push-bar. Fig. 7 is a similar view showing the push-bar depressed, having turned the carrying-wheel almost one space and raised the locking-arm, releasing the coin. Fig. 8 is a detail view of the inner end of the push-bar 30 and its shifting devices, showing the parts in position immediately before the termination of the outward travel, the inner end of the locking-arm having dropped down in front of the bar. Fig. 9 is a similar view showing the bar having completed its outward travel and 35 finishing the shifting operation, so as to complete the period of movement of the carrying-wheel. Fig. 10 is a detail view of the back portion of the apparatus, showing the locking-arm and the counterweighting arresting-arm. Fig. 11 is a detail view showing a modified form of carrier.

My invention relates to automatic vending devices wherein a rotating carrier is adapted 45 to hold or contain the articles to be vended and is intermittently operated by a coin-con-

trolled push-bar, so as to expose a special article, quantity, or number of articles at each operation.

Referring to the drawings, 2 represents the 50 case of the apparatus, upon an inner wall or supports 3 of which is mounted a stud or bearing 4, upon which is rotatably mounted a carrier 5. The carrier is preferably made in the form of a wheel having regularly-arranged pockets or spaces 6, adapted to hold a cigar or any other suitable article, and the front 7 of the case is provided with an opening 8 of suitable area and form to permit the removal of the article, with which opening the 60 pockets 6 are adapted to intermittently and successively come into register. The front 7 may be hinged to the main case and may conveniently be made of plate-glass or be provided with a pane of glass adapted to expose 65 the contents of the carrier or a portion of them immediately in advance of the opening 8, so as to indicate the contents or the condition of the apparatus whether charged or empty. 70

Extending backwardly from the carrier 5 concentric with its center is a series of pins or abutments 9, corresponding to the pockets 6, as indicated in Fig. 1. Slidingly mounted in the interior of the case in any suitable support is a push-bar 10, the stem 11 of which extends outwardly through the side of the case in a suitable bearing and is provided with a push-button 12, the push bar and button being normally retracted by a spring 13 of 80 any suitable form, secured to the push-bar and to the interior of the case. Pivotaly mounted at 14 on the push-bar is a shifting finger 15, having a tapered face 16, adapted to engage one of the pins 9 in the forward movement of 85 the push-bar, forcing it up and rotating the carrier in the direction of the arrow in Fig. 5, in which figure the pins 9 are indicated as standing in front of the shifting apparatus. The back end of the shifting finger 15 is slotted, as at 17, and is engaged by a pin 18, limiting the downward travel of its point, the 90

back end being normally held raised, as in Fig. 5, by a counterweighted lever 19, pivoted to the push-bar at 20.

In front of the finger 15 is a lug 21, provided with a cam-face 22, adapted to engage the partially-shifted pin 9 on backward movement of the bar, moving the pin up and completing the operation.

Pivoted at 23 is a locking-arm 24, the inner end 25 of which is bent around and adapted to engage the front end of the push-bar, so as to lock the push-bar against inward travel, the outer end of the locking-arm extending through a vertical slot 26 into the path of a coin adapted to travel downwardly through coin-slot 27. The outer end of the locking-arm is normally held raised in the slot by reason of the slightly greater weight of the inner end, which extends through a slot 28 or is otherwise suitably arranged, so as to stand immediately in front of the push-bar, the locking-arm being delicately balanced, so as to be sensitive to the gravitating action of the coin. 29 is an arresting-arm pivoted at 30 and having an upwardly-extending extremity 31, adapted to arrest the downward travel of the inner end of the locking-arm when depressed by the weight of the coin, thus raising the inner end 25 sufficiently far to unlock the push-bar, as in Fig. 6.

The arresting-arm has a counterweighting extension 32, adapted to raise the extremity 31, its upward movement being limited by a pin or abutment 33.

35 A coin having been dropped from the exterior of the case in the slot 27, its weight depresses the outer end of the locking-arm, raising the inner end, when the push-bar may be pushed in, whereupon the point of the finger 15 engages one of the pins or abutments 9, causing it to ride upwardly on cam-face 16, and upon releasing pressure from the push-bar the spring 13 will retract it and the cam-face 22 of lug 21 will complete the movement of the pin, 40 thus producing an intermittent rotation of the carrier equivalent to the pitch or space between the pins and moving the pockets 6 one space. The forward or inner end of the push-bar is provided with an inclined cam-face 34, which engages the end 25 of the locking-arm, tilting it upwardly and depressing its outer end, which bears down against the terminal 31 of the arresting-arm, thus releasing the coin, as in Fig. 7, which then drops 45 down through the slot into a receptacle 35 in the interior of the case. Upon releasing the push-bar the locking-arm resumes its normal position in front of the bar, locking it against further movement until released by the insertion 50 of another coin.

As will be understood, the locking-arm is balanced, and its proportions, as well as those of the coin-slot, are adjusted to be operated

by a coin of a specific size and gravity—as, for instance, a nickel—so that the apparatus can- 65 not be operated by a coin of another denomina- 70 tion.

It will be understood that the carrier 5 may be adapted to contain various articles and the shape of the pocket may be varied or several 75 cavities be arranged within the compass of one space, as by making a series of inwardly-extending cylindrical openings in which a pluri- 80 lity of cigars or cigarettes may be inserted, all of which may be exposed at one time, as 85 illustrated in Fig. 11. The carrier may also be provided with any suitable holding device— 90 as, for instance, pins—upon which stamps or other articles may be affixed, and various other adaptations of the device may be made to suit different requirements of use.

It will be understood that the front door or partition or other removable closure is to be provided with a suitable lock, so as to prevent tampering with the machine or access to 85 its interior without unlocking. Other changes or variations may be made in the design, proportions, or other details by the skilled mechanician without departing from the invention, and all such are to be considered as within 90 the scope of the following claims.

What I claim is—

1. The combination with the push-bar of a vending-machine provided at its forward end with an abutting end and a backwardly-sloping inclined cam; of a pivoted locking-lever having a terminal adapted to engage the abutting end and to be engaged by the inclined cam of the push-bar, and a pivoted counterweight-lever adapted to be depressed by the other 100 end of said locking-lever upon inward movement of the push-bar, and to be raised by said counterweight-lever upon return movement of the push-bar, substantially as set forth.

2. The combination with the push-bar of a vending-machine provided at its forward end with an abutting end and a backwardly-sloping inclined cam; of a pivoted locking-lever having a terminal adapted to engage the abutting end and to be engaged by the inclined cam of the push-bar, a coin-chute so located as to receive the other end of said locking-lever, and a pivoted counterweight-lever adapted to be depressed by the said other end of the locking-lever upon inward movement of the push-bar, and said end of the locking-lever to be raised by said counterweight-lever upon return movement of the push-bar, substantially as set forth.

In testimony whereof I affix my signature in 120 presence of two witnesses.

GEORGE W. MACKENZIE.
